UNITED STATES PATENT OFFICE.

FRANÇOIS RICHARD, OF CLEVELAND, OHIO.

DESIGN FOR AN AUTOMOBILE-BODY.

47,895.

Specification for Design.

Patented Sept. 28, 1915.

Application filed March 27, 1915. Serial No. 17,569. Term of patent 7 years.

To all whom it may concern:

Be it known that I, FRANÇOIS RICHARD, a citizen of the French Republic, residing at Cleveland, in the county of Cuyahoga and State of Ohio, have invented a new, original, and ornamental Design for an Automobile-Body, of which the following is a specification, reference being had to the accompanying drawing, forming part thereof.

Figure I is a top plan of an automobile

body showing my new design. Fig. II is a side elevation thereof.

I claim:

The ornamental design for an automobile body as shown.

FRANÇOIS RICHARD.

Witnesses:

FERN GILMORE,
CLARA B. CUMMINS.
